UNITED STATES PATENT OFFICE.

NICHOLAS SHUN, OF MINNEAPOLIS, MINNESOTA.

HAND SNOW-PLOW.

1,319,972.

Specification of Letters Patent.

Patented Oct. 28, 1919.

Application filed May 22, 1919. Serial No. 298,852.

To all whom it may concern:

Be it known that I, NICHOLAS SHUN, a citizen of Poland, residing at Minneapolis, in the county of Hennepin and State of 5 Minnesota, have invented certain new and useful Improvements in Hand Snow-Plows, of which the following is a specification.

The primary object of the invention is the provision of means especially adapted for 10 cleaning sidewalks of snow and ice easily and quickly during the forward travel of the operator.

A further object of the invention is to provide a snow plow adapted for manual 15 operation for cutting through snow and ice upon the sidewalk and being compactly foldable for storing away when not in use.

With these general objects in view the invention consists of the combination and arrangement of parts hereinafter fully described in connection with the accompanying drawings and in which like reference characters are employed throughout the views, and in which—

25 Figure 1 is a central longitudinal sectional view through the invention,

Fig. 2 is a top plan view thereof with the plow open ready for use,

Fig. 3 is a view similar to Fig. 2 with the 30 plow closed.

Fig. 4 is an enlarged transverse sectional view of the invention taken upon line IV—IV of Fig. 1, and

Fig. 5 is an enlarged horizontal detail 35 sectional view thereof.

My invention comprises a bottom or platform 10 elongated in form with a tapered forward portion 11 having a triangular nose or cutting block 12 upon the forward end 40 thereof. A push member 24 extending at an oblique angle upwardly and rearwardly of the end of the platform 10 has a cross handle 13 upon the upper free end thereof by means of which the plow is operated.

45 A plate 14 secured to the inner face of the nose 12 has a wing 15 forming a plow member hinged thereto as at 16 at each opposite sides of the invention. The wings 15 are adapted to swing inwardly substantially in contact with the adjacent oblique sides 17 of the platform 10, when the device is folded and for swinging outwardly in substantial alinement with the outer faces 33 of the nose 12 when the wings are projected with 50 the device positioned for use in plowing.

A rectangular body or actuator 18 slid-

ably mounted in a longitudinal slot 19 centrally of the platform 10 with a plate 20 beneath the platform retaining the actuator in sliding relations therewith. Outwardly 60 projecting arms 21 upon the actuator 18 have terminal eyes 22 through which elongated staples or loops 23 extend and whereby as will be evident, the movement of the actuator 18 moves the wings 15 inwardly 65 or outwardly according to the direction of travel of the actuator. In operating rod 25 is pivoted as at 26 to the rear end of the actuator 18 and extends rearwardly through a longitudinal slot 27 in the push member 70 24. A cross bar 28 upon the free end of the rod 25 beneath the push member 24 serves as a handle for moving the rod 25 and shifting the actuator 18 the bar 28 also serves as a stop, preventing the upper end of the rod 75 from passing through the slot 27.

Inclined notches 29 in the lower side of the rod 25 are adapted to selectively engage over a transverse pin 30 in the slot 27. With the plow closed as shown in Fig. 3 of the 80 drawings, the forward movement of the rod 25 forces the actuator 18 toward the nose 12 and by means of the arms 21 projects the wings 15 outwardly in their operative position in V-shaped formation for forcing 85 laterally the snow and ice during the travel of the plow therethrough. The wheels 32 are journaled at opposite sides of the platform 10 upon which the plow is adapted to travel.

The forward edge 31 of the nose 12 is formed as pointed as desired for cutting its way through the snow when the plow is pushed forwardly by means of the handle 13. A downward movement of the handle 95 13 tends to elevate the nose 12 permitting the plow to pass over obstructions which cannot be penetrated by the point 31. The plurality of notches 29 also permits the reduction of the wings 15 at different adjustments for cutting different widths of paths as may be found desirable, the engagement of the notches 29 with the pin 30 preventing the rearward movement of the rod 25 and actuator 18 and holding the blades 15 adjusted for outwardly turning the snow.

While the form of the invention herein shown and described is believed to be the preferred embodiment thereof, it will be understood that minor changes may be made 110 therein without departing from the spirit and scope of the invention as claimed.

What I claim as new and desire to secure by Letters Patent is:—

1. A snow plow comprising a tapered platform, ground wheels for the platform, a triangular block at the forward end of the platform having a cutting edge at the front of the plow adapted for engaging the work, a plate secured to the rear transverse face of the block, wings at opposite sides of the platform hinged to the opposite ends of said plate, loops upon the inner faces of said wings, the platform being provided with a longitudinal slot, an actuator longitudinally slidable upon the platform projecting through said slot, a plate secured to the actuator beneath the platform, outwardly projecting arms upon the actuator through which said loops are slidably positioned and adjustable retaining means for the actuator. 45
2. A snow plow comprising a tapered platform, ground wheels for the platform, a triangular block at the forward end of the platform having a cutting edge at the front of the plow adapted for engaging the work, a plate secured to the rear transverse face of the block, wings at opposite sides of the platform hinged to the opposite ends of said plate, loops upon the inner faces of said wings and an actuator slidable longitudinally of the platform operatively connected to said loops whereby the wings are 50
- 15 adapted for inward and outward swinging movement during the shifting of the actuator. 55
3. A snow plow comprising a tapered platform, ground wheels for the platform, a triangular block at the forward end of the platform having a cutting edge at the front of the plow adapted for engaging the work, a plate secured to the rear transverse face of the block, wings at opposite sides of the platform hinged to the opposite ends of said plate, loops upon the inner faces of said wings, the platform being provided with a longitudinal slot, an actuator longitudinally slidable upon the platform projecting through said slot, a plate secured to the actuator beneath the platform, outwardly projecting arms upon the actuator through which said loops are slidably positioned, an upwardly and rearwardly projecting push-member attached to the platform, a handle on the free end of said push-member, an operating rod pivoted to the actuator freely extending through said push-member, a stop bar upon the free end of said rod and adjustment-retaining connections between said rod and push-member. 60
4. A snow plow comprising a tapered platform, ground wheels for the platform, a triangular block at the forward end of the platform having a cutting edge at the front of the plow adapted for engaging the work, a plate secured to the rear transverse face of the block, wings at opposite sides of the platform hinged to the opposite ends of said plate, loops upon the inner faces of said wings, the platform being provided with a longitudinal slot, an actuator longitudinally slidable upon the platform projecting through said slot, a plate secured to the actuator beneath the platform, outwardly projecting arms upon the actuator through which said loops are slidably positioned, an upwardly and rearwardly projecting push-member attached to the platform, a handle on the free end of said push-member, an operating rod pivoted to the actuator freely extending through said push-member, a stop bar upon the free end of said rod and adjustment-retaining connections between said rod and push-member. 65
